WIRE FEEDING MECHANISM

David T. Theodore, East Orange, N.J., assignor to The Dore Development Co., Inc., Silver Spring, Md., a corporation

Filed Nov. 16, 1960, Ser. No. 69,617

8 Claims. (Cl. 226—167)

This invention relates to a wire feed mechanism and, more particularly, to a wire feed mechanism having a predetermined and easily adjustable amount of lost motion in the wire feeding direction. The invention is particularly adaptable to cyclic operations wherein operations are performed on a wire, with the wire stationary, during a major part of an operating cycle which includes feeding of the wire.

In my prior U.S. Patents Nos. 2,564,739 and 2,696,013, I have shown and described novel nail producing die sets easily attached to and operated by punch presses and the like, the die sets being mountable on the bolsters of such presses and operated by the vertically movable rams thereof.

In mechanical punch presses, a main drive shaft is rotated by a motor, preferably through reduction gearing and/or sheaves, and the shaft has a crank and connecting rod for reciprocating the press ram. The wire feed mechanism of the invention is designed for operation by a pitman rotatable with such shaft and, while particularly useful with such nail producing die sets as attached to and operated by such presses, is also useful in feeding wire to any other type of wire working mechanism cyclically operated by a mechanical punch press. However, solely for the purpose of providing a specific operating example of the invention, it will be described as used in feeding wire to such mechanical punch operated nail producing die sets.

Basically, the invention is based upon the principle or concept of using the wire feed mechanism associated with cyclically operable wire working mechanism as a means for introducing a controlled time delay in one operation or part of the cycle, and more particularly in that part of the cycle wherein work is still being performed on fed wire. The feed mechanism of the invention, being connected for direct operation by the rotating shaft which also, through the punch ram, operates the wire working means, necessarily operates in direct relation to the working means.

In a complete operating cycle of the punch press, the wire must be stationary during that part of the cycle wherein the wire is being worked. For example, the wire must be stationary during the cutting, pointing and heading operations of a nail producing cycle. During at least a part of the balance of the cycle, the wire must be fed or moved to the wire working means. This feeding must be effected during the time the wire working dies are opening and re-closing.

In a feed mechanism reciprocating along the wire, and considering one revolution of a pitman operating the feed mechanism, the latter is moved in one direction along the wire during approximately 180° of the cycle or revolution, and in the other direction along the wire during the succeeding approximately 180° of the cycle. For example, during the first 180° of the cycle, the feeding mechanism advances or feeds the wire. In the succeeding 180° of the cycle, the feed mechanism moves reversely along the wire with the wire being stationary. In these operations, back lash in the operating connections will occur during some of the 180° of each half cycle.

However, in many wire working operations, particularly nail production, the wire working cycle, including closing the dies, forming the head and point, severing the wire and opening the dies, utilizes more than 180° of the

2

revolution of the pitman and crank shaft. Hence, an efficient wire feeding mechanism, without appreciable back lash and looseness of connections, operating during the second half of the total cycle will start to feed wire to the working mechanism before the dies are fully open. Thus, the fed wire will encounter an obstruction in the form of the only partly opened dies. Nevertheless, such a relatively tight and efficient wire feed mechanism is essential for high speed operations.

The only way to prevent such obstruction of the wire feed is to delay the start of feeding of the wire for the initial part of the second half of the total cycle and until the dies are fully re-opened. However, such delay is not readily attainable in practice while still maintaining an overall efficient operation, particularly at high speeds.

For example, purposeful introduction of back lash and loose connections to provide the requisite time delay results in the mechanism being completely unsuited for high speed operation. Geneva gearing and other forms of intermittent motion mechanisms are also unsatisfactory and inaccurate at high speeds.

In accordance with the present invention, it has been found that quiet, smooth, efficient and accurate operation at high speeds, and in a short feed time part of the cycle, can be attained by the use of a wedge type of feed. By changing the slope of the wedges, accurate setting of the feed time is easily attained and adjusted at will.

More particularly, a pair of feed rollers are arranged one on each side of the wire to be fed, and these rollers are rotatable in a carriage or slide having a pair of wedges each engaging one of the rollers. This carriage is connected to the pitman of the crank shaft of a mechanical punch press so that the carriage is reciprocated longitudinally of the wire during each rotation of the crank shaft. As the carriage is moved toward the press, the rollers roll "down" the wedges until they firmly grip the wire, this occurring during an initial period of each half cycle, the length of the initial period being determined by the slope of the wedges. When the rollers grip the wire, the wire is then fed toward the press during the remainder or "feed time" of the half cycle. When the movement of the carriage is reversed, at the end of the half cycle, the rollers roll "up" the wedges, disengaging the wire. Suitable means, such as a second stationary wedge and roller cage assembly, is provided to prevent reverse motion of the wire.

For an understanding of the invention principles, reference is made to the following description of a typical embodiment thereof as illustrated in the accompanying drawing. In the drawing:

FIG. 1 is a side elevation view of a wire feed mechanism embodying the invention, also illustrating, somewhat schematically, associated parts of a mechanical punch press operating the feed mechanism and a wire working mechanism;

FIG. 2 is a top plan view of the feed mechanism;

FIG. 3 is a transverse sectional view thereof, taken on the line 3—3 of FIG. 2;

FIG. 4 is a transverse sectional view of the carriage, taken on the line 4—4 of FIG. 2;

FIG. 5 is a longitudinal sectional view of the carriage, taken on the line 5—5 of FIG. 4;

FIG. 6 is a bottom plan view of the carriage; and

FIG. 7 is a schematic view illustrating the wire feeding action.

Referring to FIG. 1, the wire feeding mechanism 10 of the invention is illustrated, by way of example, as arranged for feeding wire W to a wire mechanism, such as a nail producing die set of the type shown in my said prior patents as mounted on the base or bolster of a mechanical punch press whose ram is reciprocated vertically by a rotatable crank shaft 14 having a pitman 15. As

described in said patents, during its downward stroke, the ram operates the die set, through suitable cooperating links and linkage on the ram and die set, to point, head, and cut nails. This downward stroke of the ram occupies about one-half revolution of shaft 14. The other one-half of the revolution is utilized to re-open the die set and feed another length of wire W thereinto.

Wire feed mechanism 10 includes a support structure 20 mounted for longitudinal adjustment along a bolster plate or support base 16 disengagedly secured to the press. The under-surface of base 21 of structure 20 and the top surface of support base 16 are formed with cooperating keyways receiving a key 22. Structure 20 is clamped in longitudinally adjusted position on base 16 by means of studs 23. Structure 20 includes integral end walls 24, interconnected by a web 25. A shelf 25 is integral with one end wall 24 and projects horizontally outward therefrom, shelf 25 being braced by a triangular web 27.

The upper end of each end wall 24 is formed with a pair of laterally spaced apertures 28, corresponding apertures in each end wall being axially aligned. Apertures 28 receive a pair of elongated guide rods 30 which project beyond one end wall over shelf 25. Rods 30 are longitudinally anchored by a pair of drift pins 31 provided with extraction nuts 32. Each rod 30 has an axial passage 33 extending from one end to a point substantially midway between end walls 24, the inner end of each passage 33 being intersected by radial passages 34. The outer ends of passages 33 receive lubrication fittings 36.

Midway between rods 30, each end wall 24 has mounted therethrough a wire guide bushing 35, bushings 35 being coaxial and locked in place by nuts 37.

Rods 30 slidably support a carriage 40 for the wire feed means. Carriage 40 is essentially a rectangular block having a central rectangular recess 41 in which is seated the components of the wire feed means generally indicated at 60. The wire feed means is disengageably retained in recess 41 by upper and lower pairs of bars 42 secured to carriage 40 by studs 43, each bar extending partially over recess or aperture 41. Carriage 40 has central apertures 44, coaxial with guide bushings 35, and apertures 46 receiving rods 30. The laterally opposite ends of carriage 40 have vertical slots 47 forming forks.

Slots 47 receive rollers 48 on the free upper ends of rocker arms 50, 50' integral with trunnions 51, 51' disposed on either side of base 21. A T-shape reinforcing web 52 interconnects arms 50, 50' above web 26. Keys 53, 53' secure trunnions 51, 51' to rotate with a rock shaft 55 having bushinged bearing engagement in a transverse aperture 54 in base 21.

A crank arm 45 is integral with the outer end of trunnion 51 and with a reinforcing web 56 extending between arms 45 and 50. Crank arm 45 is offset angularly from rocker arms 50, 50', and its free end is apertured for connection to an elongated rod or link 17 connected to pitman 15 or to an eccentrically positioned stud. The relative radial lengths of pitman 15 and crank arm 45 are so correlated that, when crank shaft 14 is rotated, arm 45 is oscillated through a predetermined angle. Through shaft 55, rocker arms 50, 50' and rollers 48, this oscillation of crank arm 45 results in reciprocation of carriage 40 along rods 30.

Referring more particularly to FIGS. 4-7, wire feed means 60 includes laterally spaced pairs of upper and lower bars or straps 61 arranged in aperture 41 above and below a pair of interchangeable wedges 65 having sloping surfaces facing each other and converging toward each other in the direction opposite to the direction of wire feed. A pair of circumferentially grooved wire feed rollers 70 are disposed between each pair of upper and lower bars 61 and engaged with the sloping surfaces of wedges 65. Rollers 70 are retained in position by a retainer or cage 62 comprising end walls 63, 64 integrally interconnected by a circularly apertured upper web 65

having its side edges disposed closely adjacent upper bars 61. End wall 63 has a wire lead-in aperture 67 and end wall 64 has an aperture 68 coaxial with a spring seating recess 71. Recess 71 seats one end of a coil spring 75 whose other end is seated in a recess in the leading edge of aperture 41. Spring 75, through retainer 62, biases rollers 70 to roll "down" the converging edges of wedges 65.

A second carriage assembly 40', identical to carriage 10 except for being slit at its ends for clamping, is clamped to rods 30 over shelf 25. Further description of carriage assembly 40', its wedges 65', 65' and its grooved rollers 70', 70', is believed unnecessary except to state that carriage assembly 40' locks the wire W against retrograde movement upon return movement of carriage 40.

The operation of the feeding mechanism will be explained with reference to FIG. 7. When, during substantially 180° of revolution of crank shaft 14 and pitman 15, carriage 40 is moved in the wire feeding direction, the rollers 70 are at the "upper" or narrower ends of wedges 65. As carriage 40 is so moved, the wedges 65 move with it so that rollers 70 roll "down" the wedges 65 toward the thicker ends of the latter. After a pre-set movement along wedges 65, determined by the angle of slope of the readily interchangeable wedges, rollers 70 "bite into" wire W and the latter is moved in synchronism with the wedges and carriage 40. As carriage 40' is stationary, this movement of wire W rolls rollers 70' "up" the wedges 65'.

At the end of this half cycle, the motion of carriage 40 is reversed. Rollers 70 now roll "up" wedges 65, releasing their grip on wire W. Any tendency of wire W to move away from the press is resisted by rollers 70' which, upon occurrence of any such wire movement, roll "down" wedges 65' to grip wire W and prevent its retrograde movement. The delay between start of the half cycle and start of wire feeding is easily pre-set by selecting wedges 65 having the requisite angle of slope, as this angle determines the time lag before wire feeding starts in any half cycle. The indentations or "feed" marks 80 in wire W, made by rollers 70, serve to de-limit the wire pieces produced by the wire working mechanism. The feeding is smooth, both as to acceleration and rate, and readily adapted to high speed operation.

The purpose of making support structure 20 longitudinally adjustable is to position the feed mark (where rollers 70 "bite into" wire W) at such a location that it will appear at the point of the formed nail and thus will "disappear" as scrap.

While a specific embodiment of the invention has been shown and described in detail to illustrate the application of the invention principles, it will be understood that the invention may be embodied otherwise without departing from such principles.

What is claimed is:

1. Wire feeding mechanism comprising, in combination, a carriage cyclically reciprocable longitudinally of the wire and formed for passage of the wire longitudinally therethrough; a pair of wedges interchangeably mounted in said carriage on either side and laterally spaced from the path of wire movement therethrough; said wedges having facing sloping surfaces diverging in the direction of wire feed at a preselected slope angle; and a pair of rollers rotatable in said carriage in engagement with said sloping surfaces on either side of the path of wire movement; said rollers, upon movement of said carriage in a wire feeding direction, rolling along said sloping surfaces in a converging direction to grip the wire; the angle of divergence of the facing sloping surfaces of each interchangeable pair of said wedges being so pre-selected, with respect to the roller diameters and the wire diameter, that said rollers will grip the wire only after a predetermined movement of said carriage in a wire feeding direction; whereby a predetermined time delay in the wire advance during cyclical reciprocation of said carriage is attained solely by the use of

a pair of wedges whose angle of sloping surface divergence has a predetermined value coordinated with such predetermined time delay.

2. Wire feeding mechanism comprising, in combination, a carriage cyclically reciprocable longitudinally of the wire and formed for passage of the wire longitudinally therethrough; a pair of wedges interchangeably mounted in said carriage on either side and laterally spaced from the path of wire movement therethrough; said wedges having facing sloping surfaces diverging in the direction of wire feed at a preselected slope angle; a pair of rollers rotatable in said carriage in engagement with said sloping surfaces on either side of the path of wire movement; said rollers, upon movement of said carriage in a wire feeding direction, rolling along said sloping surface in a converging direction to grip the wire; the angle of divergence of the facing sloping surfaces of each interchangeable pair of said wedges being so pre-selected, with respect to the roller diameters and the wire diameter, that said rollers will grip the wire only after a predetermined movement of said carriage in a wire feeding direction; whereby a predetermined time delay in the wire advance during cyclical reciprocation of said carriage is attained solely by the use of a pair of wedges whose angle of sloping surface divergence has a predetermined value coordinated with such predetermined time delay; and means biasing said rollers in the direction of convergence of said sloping surfaces.

3. Wire feed mechanism as claimed in claim 1 including a cage embracing said rollers.

4. Wire feed mechanism as claimed in claim 3 including a cage embracing said rollers; and means engaging said cage and biasing said rollers in the direction of the convergence of said sloping surfaces.

5. Wire feed mechanism as claimed in claim 1 in which said carriage is slidably mounted on a support base; a shaft oscillatably mounted in said base; rocker arms secured to said shaft and having free ends operatively connected to said carriage; and crank means operable to oscillate said shaft to reciprocate said carriage.

6. Wire feed mechanism as claimed in claim 5 including a pitman secured to a rotatable crank shaft; and a rod interconnecting said pitman and said crank means.

7. Wire feed mechanism as claimed in claim 6 in which said crank shaft, during one-half of each revolution, is ineffective to feed the wire and, during a portion of the other half of each revolution preselectable by the degree of slope of said wedges moves said carriage in a wire feeding direction.

10 8. Wire feeding mechanism, as claimed in claim 1, in which said carriage comprises a substantially flat body having substantially parallel and flat upper and lower surfaces; said body being formed with a rectangular aperture therethrough centered on the path of wire feed; said wedges being mounted in said rectangular aperture intermediate the upper and lower surfaces of said body; a pair of bars associated with each wedge, the respective bars of each pair being disposed on opposite sides of each wedge and being substantially flush with the respective surface of said body; said bars extending toward each other sufficiently to partially overlap said rollers; and pairs of clamping straps secured to the respective surfaces of said body by removable attachment means and partially overlapping said bars to retain said wedges and rollers in assembled relation; whereby said feeding mechanism may be easily disassembled for inspection and/or repair by disengaging said attachment means, removing said straps, and removing said bars and wedges from said rectangular opening along with said rollers.
